UNITED STATES PATENT OFFICE

ANDREW LEVAGGI, OF BLOOMINGTON, INDIANA

DESIGN FOR A MIRROR

Application filed August 24, 1929. Serial No. 32,528. Term of patent 7 years.

To all whom it may concern:

Be it known that I, ANDREW LEVAGGI, a citizen of the United States, residing at Bloomington, in the county of Monroe and States of Indiana, have invented a new, original, and ornamental Design for Mirrors, of which the following is a specification, reference being had to the accompanying drawing, forming a part thereof.

The figure is a perspective of a mirror showing my new design.

The back of the mirror is plain.

I claim:

The ornamental design for a mirror as shown and described.

ANDREW LEVAGGI.
